UNITED STATES PATENT OFFICE

106,589

DESIGN FOR AN AUTOMOBILE HEATER HOUSING

Samuel Briskin, Chicago, Ill., assignor to Excel
Auto Radiator Company, Chicago, Ill., a cor-
poration of Delaware

Application August 27, 1937, Serial No. 71,356

Term of patent 3½ years

To all whom it may concern:

Be it known that I, Samuel Briskin, a citizen of the United States, residing at Chicago, in the county of Cook and State of Illinois, have invented a new, original, and ornamental Design for Automobile Heater Housing, of which the following is a specification, reference being had to the accompanying drawing, forming part thereof.

Fig. 1 is a front elevation of an automobile heater housing showing my new design.

Fig. 2 is a side elevation of the housing looking from the left of Fig. 1, and

Fig. 3 is a side elevation of the housing looking from the right of Fig. 1.

I claim:

The ornamental design for an automobile heater housing as shown.

SAMUEL BRISKIN.
